ADHESIVE SHEET DISPENSER

Arthur A. Anderson, Rose Township, Ramsey County, and Ralph H. Munson, St. Paul, Minn., assignors to Minnesota Mining & Manufacturing Company, St. Paul, Minn., a corporation of Delaware

Application January 10, 1941, Serial No. 373,954

6 Claims. (Cl. 164—845)

This invention relates to a dispenser for normally tacky or pressure-sensitive adhesive sheeting in roll form, such adhesive tape having a paper or cloth backing, or a backing of a cellulosic film, coated on one side with a tacky adhesive which is adherent without the necessity of activation by water, solvents or heat, and which can be unwound from rolls thereof without transfer or offsetting of the adhesive, due 10 to the highly cohesive nature of the adhesive.

One problem in using sheets carrying such tacky pressure-sensitive adhesive is the difficulty in removing them in desired lengths from supply rolls.

15 The present invention has among its objectives the following:

To provide a simple device whereby a predetermined length of pressure-sensitive adhesive sheeting is accurately measured and thrust out 20 in position ready for grasping and severance, with its adhesive portion free from contact with any object except at its inner end;

To provide a dispenser which can be easily 25 adjusted to vary the predetermined unit length of tape within a substantial range, and which can be operated to dispense tape accurately measured in lengths which are multiples of the unit length, while permitting the dispensing of desired fractional lengths when something less 30 than a unit length (or multiple thereof) is desired;

To provide such a device wherein the cutting means will not become clogged with adhesive;

To provide such a device wherein the severed 35 edge of each length will be a smooth, straight cut;

To provide such a device wherein the severing of each length may be by "tearing" it off with one hand rather than by use of a mechanical 40 cutting means, but so arranged and equipped that such "tearing" may be done without disturbing the alignment of the undisposed portion of the tape in the machine; and,

To provide such a device which may be entirely 45 manually operated but which requires the use of only one hand at any time when dispensing.

The machine that is described and illustrated in the following description and drawings as 50 illustrative of our invention is a portable manually operated tape dispenser, particularly suited for use on store counters to dispense pressure-sensitive adhesive tape used in sealing packages.

In the accompanying drawings the end of the 55 machine at which it is operated and from which

the tape is dispensed for use is to be called the front end.

Figures 1 and 2 are side elevations of the right and left sides respectively (as one faces the machine at its front end). 5

Figure 3 is a front elevation.

Figure 4 is a vertical section of the draft wheel and clutch mechanism taken on the line 4—4 in Figure 3.

Figures 5 and 6 are vertical sections taken on 10 lines 5—5 and 6—6, respectively, in Figure 3; and Figure 7 is a vertical section taken on the line 7—7 in Figure 1.

Figures 8 and 9 are side and front elevation 15 views of the stripper wheel.

To the base 11 is rigidly attached the upright frame 12 which, in the present embodiment, is cast in one long relatively thin piece with various projecting lugs at proper points to which are attached the various parts of the machine, all 20 of said parts being supported directly or indirectly by the frame 12. Base 11 may be of heavy weight to prevent movement of the portable machine during use. 15

The supply roll R of pressure-sensitive adhesive 25 tape S is carried on the tape roll holder drum 25 towards the rear of the machine while the mechanism for withdrawing the tape from the supply roll and dispensing it in lengths ready for use is towards the front. 30

Tape holder drum 25 may be of a size to receive the standard commercial sizes of rolls of pressure-sensitive adhesive tape such as that sold under the trade-mark "Scotch," for example, but if desired, the machine may be provided 35 with several interchangeable drums of varying sizes.

The periphery of tape drum 25 is provided at intervals with ridges 25a extending parallel to the drum's axis so as to provide a tight fit between the drum and the roll of tape notwithstanding the slight variance in size of rolls that are used from time to time. The ridges also help to prevent slipping. 40

Tape drum 15 is journaled onto axle-bolt 26 45 so as to turn freely thereon between the head 26a and a flanged part so as to be stopped against lengthwise movement. Lug 12b is provided as a part of frame 12 to provide adequate support for axle-bolt 26 which pierces the lug 50 at right angles to the upright frame 12 and parallel to base 11. The end of axle-bolt 26 is in threaded engagement with lug 12b, said engagement being sufficiently tight to make the pin 55 relatively rigid in the frame. Head 26a is

knurled to form a thumb-turn. The axle-bolt may be turned by the thumb-turn to permit adjustment of the tape drum 25 laterally in respect to the machine as a whole so as to adjust roll 5 R of tape S behind draft wheel 32 in proper alignment.

The tape S is withdrawn from the supply roll R and projected through the machine by reason of its temporary adherence to the periphery of 10 the draft wheel 32 which is a part of the dispensing mechanism at the forward part of the machine.

Draft wheel 32 is mounted to rotate freely on shaft 27b. Just below draft wheel 32 the frame 15 12 is provided with lug 12f (Figure 3). At the right of draft wheel 32 there is a circular side plate 27 which is provided at its lower edge with lug 27a. Lugs 12f and 27a register with each other so that they may be held together by 20 screws 35 which are in threaded engagement with lug 12f. Shaft 27b is held rigidly in plate 27 so that it is rigid in relation to the upright frame 12, perpendicular thereto and parallel with the axis of the tape holder drum 25.

25 The periphery of draft wheel 32 to which tape S temporarily adheres as it is being drawn through the machine, is straight knurled in lines parallel to its axis. A peripheral groove 32a is cut to lie in a plane perpendicular to the axis 30 of wheel 32. It limits the transverse extent of the tape's contact with the draft wheel's periphery and is positioned so as to leave on either side of the groove an area of knurled surface sufficient to permit tape S to adhere to said 35 knurled surface when the tape is positioned so that the small stripper wheel 37 contacts the tape. Groove 32a is of a width to admit the stripper wheel arm 36 without contact with draft wheel 32, and deep enough so that stripper wheel 37 may be inserted in the groove to a depth of 40 about half the diameter of stripper wheel 37.

Stripper wheel arm 36 is held in place by being shaped at its lower end to register with lugs 12f and 27a (Figure 5) and pierced by holes 36b to 45 admit screws 35, holes 36b being sufficiently large to permit adjusting the position of arm 36 to bring stripper wheel 37 into proper position relative to the severing knife 33 and draft wheel 32, after which screws 35 are tightened so that 50 arm 36 is held rigid by the pressure of lug 27a and of lug 12f on either side. At its upper end stripper wheel arm 36 is split to form two arms 36a, having between them sufficient space to 55 permit stripper wheel 37 to turn freely on the pin 37b which is journaled in arms 36a (Figures 8 and 9). Stripper wheel 37 is preferably quite small in diameter, as compared with the draft wheel, and is shaped so that its periphery 37a is very narrow or knife-like. It is located a substantial distance forwardly of the point at which 60 the tape first contacts the draft wheel.

Arm 12d extends upwardly from the top of frame 12 and to it is removably attached (by screws 34) a fixed transverse shearing blade or 65 knife 33, located tangentially and in close proximity to the periphery of draft wheel 32 and with its edge pointing toward, and in close proximity to, stripper wheel 37, so that adhesive tape passes under the shearing edge and then over the stripper 70 per wheel during rotation of the draft wheel (see Figure 5). The advancing tape is projected outwardly by the stripper wheel, and can be severed by grasping the end of the tape and pulling the tape against the blade. The blade or knife 75 has a straight edge, as distinguished from a saw-

tooth or serrated edge, permitting of a clean cut. The knife edge is preferably only sufficiently far from draft wheel 32 to permit free movement of the wheel when its periphery is carrying a thickness of tape, and sufficiently above stripper 5 wheel 37 to permit tape to be bent by stripper wheel 37 outwardly away from draft wheel 32, and sufficiently close to stripper wheel 37 so that tape is stripped off directly after it passes the knife edge.

10 Pin 40 which is rigidly attached to frame 12 at a point below draft wheel 32 where the frame is reinforced by lugs 12e, carries idler pulley 39, around which the tape may be trained (see S' in Figure 1), whenever a greater pull by draft 15 wheel 32 is needed than is provided by running tape S direct from roll R to wheel 32.

Draft wheel 32 is driven by the power wheel 24a through the clutch cam 24c which is rigidly attached to the wheel 24a. The side of draft 20 wheel 32 which is adjacent to power wheel 24a is cut away in the form of a deep and wide concentric groove designed to receive cam 24c so that draft wheel 32 may turn freely in close proximity to power wheel 24a without contacting 25 cam 24c.

Similarly, there is rigidly attached to side plate 27 the clutch cam 27c. Also the adjacent side of draft wheel 32 is cut away to receive the cam and to permit wheel 32 to turn freely in close 30 proximity to plate 27 without contacting cam 27c.

Referring to Figure 6, the spaces 28a, 29a and 30a between the cam 24c and the inside rim of draft wheel 32 are of a size to receive rollers 28, 29 and 30. When any one of the rollers is located in relation to its space as is roller 29 in 35 Figure 6, such roller is free to turn. But the spaces 28a, 29a and 30a taper so that when a roller is located as are rollers 28 and 30 in Figure 6, it is wedged tight between cam 24c and 40 wheel 32 and cannot turn.

Similarly, the space 31a (Figure 4) between cam 27c and rim of wheel 32 permits roller 31 to turn freely. But the space tapers so that when roller 31 is located in the particular position 45 shown in Figure 4, the roller is wedged tight and cannot turn.

In actual practice the taper of the spaces is such that only a slight change of position of the roller will either wedge the roller or render it 50 free to turn. A greater distance is shown in the drawings for sake of clarity.

Referring to Figure 6, when the mechanism is motionless, at least one of the three rollers will be held by gravity in a wedged position between 55 cam 24c and wheel 32 (like roller 28) so that when power wheel 24a, and with it cam 24c, is turned clockwise, draft wheel 32 is moved in unison therewith. But when power wheel 24a, and with it cam 24c, is moved counter-clockwise, all 60 the rollers 28, 29 and 30 are rolled away from their wedged position to where they are free to turn so that no turning impulse is applied to draft wheel 32.

65 To insure against any slight turning of wheel 32 in a counter-clockwise direction, the clutch cam 27c and its roller 31, as previously described, are provided. If the working of the parts or snap of the tape or other cause tends in any way to turn the draft wheel counter-clockwise 70 (Figure 4), the roller 31, being held by gravity in wedged position in its space, instantly brakes the draft wheel. But when draft wheel 32 is turned clockwise by force of power wheel 24a, the roller 31 is moved toward its space 31a where 75

it is free to turn, and being free to turn, it cannot brake the wheel 32.

If there were any backward rotation of draft wheel 32, accuracy of measurement of dispensed lengths would be lost; also it would cause spillage of the tape due to overlapping of adhesive coated surfaces upon each other.

Instantaneous braking of the draft wheel 32 against backward turning, as contrasted with the delayed braking action secured by other one-way driving mechanisms, such as a ratchet, provides positive prevention of even the slightest shortening of the length of tape that has been projected. Likewise, since at least one of the three rollers 28, 29 or 30 is always in wedged position, the draft wheel 32 turns instantly as soon as power wheel 24a is turned, so that the length of tape projected will coincide precisely with the amount of turn of the power wheel 24a, the length of whose turn is measured and controlled accurately as hereinafter described.

Accuracy of measurement is particularly desirable in the dispensing of label tape which is printed to form a series of labels, such as airmail stickers. The mechanism herein described is inherently of a kind that minimizes inaccuracies and the accumulation of inaccuracies and permits the reduction of backlash to a negligible amount.

Power wheel 24a which turns draft wheel 32 is actuated by sprocket wheel 24, the two wheels 24 and 24a being spaced apart and joined by a common journal 24b. The upright supporting frame 12 is provided, at its upper forward portion, with lug 12c which is pierced in a direction perpendicular to frame 12 and parallel with the axis of the tape holder drum 25 to form a bearing which receives the journal 24b. Wheels 24 and 24a and their journal 24b are all rigid in relation to each other but free to turn in the bearing that pierces lug 12c.

The journal 24b is pierced to receive shaft 21b which is rigid in relation to lug 12c and frame 12 but is adjusted so that journal 24b turns freely between 12c and 21b.

The sprocket wheel 24 is actuated by chain 23 which passes over it in operative engagement therewith, being attached at its forward end to pin 19a on the forward part of the operating lever 19 and being attached at its rear end to coil spring 22 which is loaded to draw the chain rearwardly. The rear end of spring 22 is anchored to arm 12a which is an extension of frame 12. On the front end of the lever 19 is fixed a handle 20 of a size and shape to receive the operator's hand or finger when the lever is to be pressed downwardly.

The operating lever 19 is attached to the machine in such a manner that by a downward stroke it draws chain 23 downwardly and forwardly so as to turn sprocket wheel 24 clockwise (looking towards the left side of the machine).

At the point where arm 12a is joined to the frame 12, the rear end of lever 19 is pivoted to the frame by the pivot 21. The pivot has adequate support in the frame because the thickness of the frame is supplemented at this point by the thickness of the arm 12a. One of the ends of pivot 21 is formed into a screw-head 21a to permit adjustment of the pivot. Pivot 21 is in threaded engagement with frame 12, said engagement being sufficiently tight to make the pivot relatively rigid in the frame. The part of

the pivot which passes through lever 19 is not threaded, and is journaled into the lever.

To prevent its lateral movement, the lever 19 is flanked on either side by guide plates 13 and 14. Plate 14 is pivoted to the frame 12 by pivot 54. Plate 14 is made thicker at this point by lug 14c which is a part of plate 14, and lug 12h is likewise provided as a part of frame 12, so that pivot 54 may have adequate bearing. Pivot 54 may be in threaded engagement with 10 either the frame or plate and journaled into the other. Plate 14 is also removably attached to another part of frame 12 by lug 14a, which is a part of plate 14. At the point where lug 14a meets frame 12, lug 14a is reduced in size to form 15 pin 14b which extends through slot 12g to the other side of frame 12. Pin 14b is threaded at its outer end to receive thumb-screw 18. By loosening screw 18, plate 14 may swing about pivot 54 to the extent allowed by slot 12g. 20

Plate 13 is rigidly attached to plate 14 by screws 15 and 16. The plates are held apart enough to permit passage of lever 19 between them by collars around the screws and between the plates (like collar 17). 25

Collar 17 also limits the downward stroke of lever 19, and a similar collar around screw 16 limits the upward stroke so that by loosening screw 18 and raising the front ends of plates 13 and 14, the stroke is shortened. Thus, the 30 unit length of tape that is automatically measured by the machine may be accurately varied by a simple resetting of the machine without substitution of new parts. 35

Mode of operation

Supply roll R of pressure-sensitive adhesive tape S is mounted on the drum 25, and by turning thumb-turn 26a, the drum may be adjusted 40 laterally to align it directly behind the draft wheel 32, so that when the tape is threaded through the machine it will contact the stripper wheel 37.

The tape S, being wound on the roll R with 45 its adhesive side facing inwardly, is led from roll R over draft wheel 32, the adhesive side contacting the draft wheel's periphery, until the forward edge of the tape extends as far as the cutting edge of knife 33. 50

The normal position of the lever 19 is at the uppermost limit of its stroke, as in Figures 1, 2 and 3. It is held there by tension of spring 22. The hand of the operator presses lever 19 down to the limit of its downward stroke, i. e. 55 until lever 19 is stopped by collar 17 (Figure 3). Collar 17 may be raised or lowered to limit the length of the stroke and thereby to limit the unit length of tape dispensed to any length within 60 that dispensed by the lever's longest stroke, by raising or lowering the lever guide plates 13 and 14 and fixing them in the desired position by tightening thumb-turn 18. 65

The downward stroke of the lever 19 pulls 65 chain 23 which turns sprocket wheel 24 clockwise (as one faces the left of the machine as in Figure 2), and since power wheel 24a and the sprocket wheel are rigidly fixed to a common journal 24b, the wheel 24a and its clutch cam 70 24c move clockwise in unison with the sprocket wheel. The cam 24c, through at least one of the rollers 28, 29 and 30 (in a manner previously described), imparts this impulse without lag or loss of motion to the draft wheel 32 so that 75

draft wheel 32 also turns clockwise in unison with the sprocket wheel.

The adhesion of the tape S to the draft wheel's periphery either when the tape is threaded directly from roll R to wheel 32 or by way of idler pulley 39 (as S' is threaded in Figure 1) is sufficient to withdraw the tape from the roll R and project it beyond the cutting edge of the knife 33.

10. Normally, the tape would continue to adhere to the draft wheel as the wheel turns, but just as the tape moves beyond the knife edge, the tape meets the stripper wheel 37 and is forced off the peripheral surface of the draft wheel and directed outwardly away from the machine. As stripper wheel 37 is the forwardmost part of this section of the machine, and since the tape has some degree of stiffness, the advanced portion of tape projects clear of the machine and 15 in position to be readily grasped.

Straight knurling crosswise of the draft wheel 32, among other functions, provides the wheel with greater traction upon the tape being removed from the roll R, since the pull is in a direction tangential to the draft wheel 32. It also causes the wheel to exert less resistance to stripping off of the tape due to the limited contact area.

At the end of the down stroke of lever 19, the 30 lever is released and is returned to its normal position by spring 22. In so doing, it causes sprocket wheel 24 to turn counter-clockwise and with it wheel 24a and cam 24c. But as previously described, by reason of the rollers 28, 29 35 and 30, no motion is conveyed to draft wheel 32 when wheel 24a moves counter-clockwise. Also, as previously described, draft wheel 32 is locked against any counter-clockwise or "backward" movement by clutch cam 27c on side plate 27 and 40 by roller 31.

Therefore, when the lever 19 is released by the operator all the mechanism is automatically returned to its original position in readiness for dispensing the next length, but during such return the draft wheel 32 remains stationary so that the projected length of tape S is still held out away from the machine ready to be cut off by pulling it diagonally up and across the knife edge. To do this, the operator may use the same 45 hand that he used to press the lever. His other hand is free at all times to hold the article to which the tape is to be applied. If longer strips are desired, they may be secured by repeated de- 50 pressions of the lever before the length is cut off.

55. During cutting, the slightly sideward pull on the tape does not disturb the alignment of the unprojected portion partly because of the adhesive engagement of the tape with the draft wheel and the close set of the knife to the draft wheel. This permits the use of a straight knife edge in place of the old sawtooth type of cutter to which bits of adhesive will stick and which leaves a ragged edge.

A further insurance against the knife becoming gummed with adhesive is that the machine is designed to apply the cutting force to the non-adhesive side of the tape.

This freedom from contact between adhesive and knife prevents adherence of the tape to the 70 knife so that the unprojected portion is free to be thrust forward when the draft wheel turns to advance the next length.

The illustrated embodiment may be entirely encased, with operating lever 19 and handle 20 extending through an opening therein and with a

small opening at the front through which the tape is thrust by the machine, such opening shaped to expose enough of the knife 33 to permit severing the projecting tape as described above. In such an arrangement the thumb-turn 18 may project through an arc shaped slot in the casing, calibrations being marked on the casing adjacent the slot to show what length of tape will be dispensed when the thumb-turn 18 is set at a given point.

10. If atmospheric conditions curl the tape so as to make it desirable to augment the outward guidance of projected tape, an extra guide wheel A or roller of small diameter, similar to stripper wheel 37, may be rotatably held by an arm forwardly of the stripper wheel 37 and in line therewith to guide the projected tape outwardly still farther away from contact with the machine or casing.

15. The illustrated embodiment is suited to handling tape, but the invention may take form in machines where draft wheel 32 is of great width and where there are a plurality of stripper wheels 31 to handle sheets of material wider than the sheets commonly called "tape." The sprocket 25 wheel 24 may be power driven, or lever 19 may be operated by a foot treadle.

We claim:

1. In a pressure-sensitive adhesive sheet dispenser, a holder for a supply roll of the adhesive sheeting, draft wheel means for withdrawing the adhesive sheeting from the roll by adhesive contact therewith, having a grooved periphery to limit the transverse extent of contact, one-way driving means for rotating the draft wheel in a 35 direction to withdraw adhesive sheeting from its roll and means for preventing backward rotation of the draft wheel, a small rotatable stripping element extending into the grooved portion of the draft wheel and located a substantial distance forwardly of the point at which the adhesive sheeting first contacts the draft wheel, adapted to separate the adhesive sheeting from the draft wheel and direct it outwardly as the latter rotates, a substantially fixed transverse 45 shearing blade located in close proximity to the periphery of the draft wheel and with its edge pointing toward, and in proximity to, said stripping element, so that adhesive sheeting passes under the shearing edge and then over the stripping element during rotation of the draft wheel and the adhesive sheeting can be severed by grasping the projecting part and pulling the non-adhesive backing against the shearing edge without substantial removal of the rearward portion 50 of the adhesive sheeting from the draft wheel and without drawing it out of alignment.

2. The device of claim 1 in which the means for rotating the draft wheel includes a lever and means for controlling the stroke of the lever so 60 as to vary the unit length of adhesive sheeting dispensed with each stroke of the lever.

3. The device of claim 1 in which the stripper element is a rotatable wheel of an extremely small 65 diameter as compared to the draft wheel's diameter and having an edge-like periphery.

4. The device of claim 1 in which the draft wheel's peripheral surface is knurled.

5. The device of claim 1 in which the knife blade has a straight edge located close to the 70 draft wheel with a clearance not substantially more than sufficient to permit passage of the adhesive sheeting between the knife and the draft wheel, and in which the stripping element is a wheel of very small diameter compared with the 75

diameter of the draft wheel and with an edge-like periphery located so close to the knife edge as to strip the adhesive sheeting from the rotating draft wheel directly after the adhesive sheeting has passed beyond the knife edge.

6. In a portable dispenser for pressure-sensitive adhesive tape, adapted for counter use in stores, means for supporting a supply roll of tape, a draft wheel having its peripheral surface straight knurled in lines parallel to the wheel's axis for withdrawing the tape from said roll and having a grooved periphery to limit the transverse extent of contact, one-way driving means for rotating said draft wheel in a direction to withdraw tape from the roll, said means being adapted to impart its impulse to the draft wheel without loss of motion, and means for preventing backward rotation of the draft wheel, an operating lever for actuating said driving means and means for adjusting the stroke of the lever, a stripper wheel having an edge-like periphery and

held in the grooved portion of the draft wheel and extending into said grooved portion a sufficient distance so that tape adhering to the draft wheel's periphery will be lifted off said periphery by said stripper wheel as the tape is advanced 5 against the stripper wheel, said stripper wheel having an extremely small diameter as compared to the draft wheel's diameter, a fixed transverse shearing blade having its shearing edge in close proximity to the draft wheel at a point in relation to the stripper wheel such that tape will pass the shearing edge directly before it meets the stripper wheel, so that tape can be severed by grasping the projecting part and pulling the non-adhesive backing against the shearing edge 10 without substantial removal of the rearward portion of the adhesive sheeting from the draft wheel, without drawing it out of alignment and without contacting the blade with the adhesive.
